UNITED STATES PATENT OFFICE.

WILLIAM B. MUCKLEROY, OF HOUSTON, TEXAS, ASSIGNOR TO FOGLE WEST UNDER-TAKING COMPANY, OF HOUSTON, TEXAS, A CORPORATION.

DESIGN FOR A BURIAL-RECEPACLE COVER.

Application filed June 11, 1928 Serial No. 27,070. Term of patent 14 years.

To all whom it may concern:

Be it known that I, WILLIAM B. MUCKLEROY, a citizen of the United States, residing at Houston, in the county of Harris, State of Texas, have invented a new, original, and ornamental Design for a Burial-Receptacle Cover, of which the following is a specification, reference being had to the accompanying drawings, forming a part thereof, wherein Figure 1 shows a perspective view of the receptacle and Figure 2 shows a fragmentary sectional view thereof.

What I claim is:—

The ornamental design for a burial receptacle cover as shown.

WILLIAM B. MUCKLEROY.
